UNITED STATES PATENT OFFICE

FRANK EDWARD ELMORE, OF BOXMOOR, ENGLAND.

SEPARATION OF MATERIALS BY FLOTATION.

Application filed April 23, 1927, Serial No. 186,114, and in Great Britain July 16, 1926.

This invention relates to the separation of materials by flotation, more particularly to the cleaning of coal and the concentration of ores and the like (all such materials being for brevity hereinafter termed "mineral") by flotation, and in particular relates to improvements in the "vacuum" process of flotation and the apparatus used therein.

In the said "vacuum" process as heretofore conducted the pulp of mineral and water has, after agitation with oil or similar agent, been sucked up through a pipe from a reservoir into the separating chamber by the vacuum maintained therein. The velocity of the pulp in this pipe has generally been made such as to insure that the heaviest mineral grains are carried up into the separating chamber. As the pulp rises in this pipe and approaches the separating chamber, the pressure on the pulp progressively decreases, thus causing a liberation of the dissolved and contained gases and their expansion in the pulp. Such expansion leads to an increase in the volume of the pulp and a corresponding increase in its velocity up the pipe.

By observation of what occurs in the pipe I have found that the considerably increased velocity thus produced leads to turbulence and a detachment of clean mineral grains from the bubbles of gas liberated by the decreased pressure. The mineral grains so detached are to a considerable extent lost in the residues.

In some forms of apparatus (such as the apparatus described in British specification No. 191,383) the pulp is admitted in a horizontal or approximately horizontal direction into the separating chamber at such velocity as to cause rotation of the whole of the pulp therein. By observing what occurs in such apparatus I have found that the rotation leads to the creation of eddying currents or turbulence in the separating chamber and a loss of clean mineral by its detachment from gas bubbles; also that a considerable loss of mineral also occurs in the horizontal part of the inlet pipes, owing to the rubbing of the bubbles laden with clean mineral along the underside of the top of the pipe, which causes detachment of clean mineral from the bubbles. The same effect is also produced by the bends in the pipe where it turns from the vertical to the horizontal position.

Mechanical rakes or stirring arms in the separating vessel (such as described in Brit-

ish specification No. 29,282 of 1904) have a similar effect in detaching mineral grains from the bubbles.

All these defects are particularly important in treating coarse particles. 60

By the use of my improved "vacuum" process and apparatus these defects are largely overcome, and I am enabled, for example, successively to treat coal crushed to a larger size and with a larger through-put than hitherto. 65

According to the invention the pulp of water, mineral and selective agent, such as oil, is sucked up into a separating chamber as a substantially vertical stream, which is free from horizontal portions or changes of direction and travels at approximately constant velocity. In this manner turbulence is minimized and the bubbles and attached mineral rise quietly. 75

One mode of obtaining the substantially constant velocity consists in arranging that the stream shall have an increasing cross section in the upward direction. The bubbles and attached mineral should be separated from the stream in the separating chamber without aid of mechanical rakes or stirrers. 80

In a preferred form of the process the depleted pulp, during its descent in the separating chamber, is given a rotary movement 85 by the admission of one or more tangential streams of water under pressure, in order to enable a further portion of clean mineral grains to rise and be separated, any communication of rotary movement to the main body of flotation froth above being largely prevented by stationary baffles arranged around the point of entry into the separating chamber of the non-turbulent stream of pulp. 95

The invention further consists in apparatus suitable for carrying out my improved process, said apparatus comprising a separating chamber having the usual conical or like contracted upper part connected with a vacuum pump, an outlet pipe for the concentrates, and an outlet for the depleted pulp, and said chamber also having a central substantially vertical suction-pipe for the pulp, free from bends or horizontal portions and so tapered in vertical section that the rising pulp as it expands under the action of the falling pressure continues to ascend therein as a non-turbulent stream of approximately constant velocity. 110

The foregoing features of my invention and other features thereof will now be explained with reference to the accompanying drawing which represents a vertical section 5 through an apparatus suitable for my improved vacuum process.

a is a conical vessel having an upper conical part *b* which has a delivery throat *c* at its summit. This throat is surrounded by a receiver *d* which is closed, save for a pipe connection *e* leading to a vacuum pump *e'* from the upper part, and an outlet opening *f* at its lower part connected with a discharge pipe *g* extending downwards into a launder *h*.
10 Into this pipe there extends at a suitable point a downwardly directed jet *i* connected with a water supply. The end of pipe *g* is sealed under water or fitted with a non-return valve.
15

The open bottom of vessel *a* is connected 20 with a pipe *k* which extends downwards into the launder *l* and is closed at its lower end by a valve *m*. The stirrup *n* which carries this valve is connected with a lever *o* centered at *p* and connected at its other end by rod *q* with 25 a lever *r* centered at *s* and subject to the action of a rotating cam *t*.

A rising pipe *u* connected by a U-bend *v* with a pulp hopper *w* extends axially in the vessel *a* to about the junction of the vessel 30 with its upper part *b*. This pipe expands upwardly and its open upper end has a number of co-axial rings *x* forming circular louvres. From this portion of the pipe extend radial baffles *y*. *z* is a jet extending more or less tangentially into the vessel *a* and connected with a water supply.
35

The operation of the apparatus is as follows, it being assumed, as an example, that the material under treatment is finely subdivided coal.
40

The pulp (a mixture of the material under treatment, water and one of the known selective agents, for instance oil), after having been stirred or agitated as is well understood, 45 is fed into the hopper *w* and the vacuum pump connected with pipe *e* is put in action. The pulp is sucked up the pipe *u* and fills the vessel *a* *b* and the pipe *k*. The cam *t* is set in rotation to open periodically the valve *m*, the 50 extent of such opening being adjusted by means of a turnbuckle *q'*. The bubbles of gas liberated from the water in the pulp which is rising up the pipe *u*, as well as the gas adsorbed on or in the coal particles, attach themselves to the particles of coal in preference to the particles of mineral matter forming a 55 part of the ash. As the bubbles ascend the pipe they grow in size and there is a tendency for the volume of the pulp to increase, accompanied by a corresponding increase in its 60 velocity up the pipe. This latter tendency is counteracted by the increasing diameter of the pipe, so that the pulp rises in the latter as a stream having approximately constant velocity and without turbulence. Since there

are no bends or turns in the pipe *u* there is little tendency for the particles which are buoyed up by attached bubbles to become detached from the bubbles by friction against surfaces.
70

As the rising pulp leaves the tube *u* the heavier particles of ash-material which have no bubbles attached to them and begin to descend against the stream, escape through the openings between the rings *x* and pass into vessel *a*. Were such particles allowed to continue to descend within the pipe *u* they might cause particles of coal to become detached from their gas bubbles.
75

The particles of coal carried by the adhering bubbles continue to rise in the upper part *b* of the vessel and finally pass through the throat *c* into the receiver *d* which they leave by the pipe *g*.
80

In treating some pulps a voluminous froth is produced which is discharged too slowly by the pipe *g*, the through-put of the machine being thus reduced. To overcome this objection means may be adopted for reducing the pressure in this pipe and increasing the velocity therein, the means here shown being the ejector jet *i* supplied with water under pressure.
85

The ash constituents collect in the vessel *a* and descend the pipe *k* ultimately escaping past valve *l* as this is periodically opened by action of cam *t* on lever *r*. This opening and closing of the valve produces a pulsation of the contents of the vessel *a* *b* which prevents clogging of the coal in the upper part *b* and the formation of channels therein. Such channels would allow the water alone to flow away without any coal passing down the pipe *g*.
95

Since some particles of coal having adhering bubbles find their way together with the ash constituents into the vessel *a*, it is advantageous to impart to the contents of this vessel a rotary movement to aid the ascent of the coal particles unimpeded by the descent of the ash constituents. For this purpose water under pressure is admitted into the vessel *a* through the aforesaid tangentially directed jet *z*. In order that the rotary movement may be communicated as little as possible to the contents of the upper part *b*, baffle plates *y* extend radially from the mouth of the pipe *u* to the periphery of part *b*.
105

Having now particularly described and ascertained the nature of my said invention and the best means I know of carrying the same into practice, I claim:
120

1. A vacuum process of separating materials by flotation which process comprises agitating the material with water and a selective agent to produce a pulp containing elastic fluid causing the pulp to ascend under a reduced pressure as a substantially vertical stream free from changes of direction and travelling at approximately constant veloc- 125
130

ity into a body of liquid wherein selected particles of the material ascend while others descend.

2. A vacuum process of separating materials by flotation which process comprises agitating the material with water and a selective agent to produce a pulp containing elastic fluid, causing the pulp to ascend under a reduced pressure as a substantially vertical stream having an increasing cross section in the upward direction compensating for increase in volume of the ascending pulp due to expansion of elastic fluid contained therein so that the ascending pulp travels at approximately constant velocity and causing the stream of ascending pulp to enter a body of liquid wherein selected particles ascend while others descend.

3. A vacuum process of separating materials by flotation which process comprises agitating the material with water and a selective agent to produce a pulp containing elastic fluid, causing the pulp to ascend under a reduced pressure as a substantially vertical stream free from changes of direction and travelling at approximately constant velocity into a body of liquid wherein the clean mineral particles ascend while the depleted pulp descends and imparting rotary movement about a substantially vertical axis to that part of the body of liquid in which the depleted pulp is descending.

4. A vacuum process of separating materials by flotation which process comprises agitating the material with water and a selective agent to produce a pulp containing elastic fluid, causing the pulp to ascend under a reduced pressure as a substantially vertical stream having an increasing cross section in the upward direction compensating for increase in volume of the ascending pulp due to expansion of elastic fluid contained therein so that the ascending pulp such that it travels at approximately constant velocity causing the stream of ascending pulp to enter a body of liquid wherein the clean mineral particles ascend while the depleted pulp descends and imparting rotary movement about a substantially vertical axis to that part of the body of liquid in which the depleted pulp is descending.

5. Apparatus for a vacuum process of separating materials in a pulp by flotation, comprising a separating vessel, a substantially vertical suction pipe having an increasing cross-section in the upward direction and extending upwardly into the said vessel, and means for sucking pulp up the said pipe into the said vessel.

6. Apparatus for a vacuum process of separating materials in a pulp by flotation, comprising a separating vessel, a substantially vertical suction pipe having an increasing cross-section in the upward direction and extending upwardly and co-axially into the

said vessel to a level about the middle of the height thereof, and means for sucking pulp up the said pipe into the said vessel.

7. Apparatus for a vacuum process of separating materials in a pulp by flotation, comprising a separating vessel, a substantially vertical suction pipe having an increasing cross-section in the upward direction and extending upwardly and co-axially into the said vessel to a level about the middle of the height thereof, at least one ring of larger diameter than the pipe forming a circular louvre opening in the upper part of the pipe, and means for sucking pulp up the said pipe into the said vessel.

8. Apparatus for a vacuum process of separating materials in a pulp by flotation, comprising a separating vessel, a substantially vertical suction pipe having an increasing cross-section in the upward direction and extending upwardly and co-axially into the said vessel to a level about the middle of the height thereof, a number of co-axial rings of successively larger diameter than the pipe arranged to form circular louvre openings at the upper part of the pipe and means for sucking pulp up the said pipe into the said vessel.

9. Apparatus for a vacuum process of separating materials in a pulp by flotation, comprising a separating vessel, a substantially vertical suction pipe having an increasing cross-section in the upward direction and extending upwardly into the said vessel, at least one jet arranged to deliver water under pressure in substantially tangential direction into the said vessel at a part thereof which is below the level of the upper end of said vertical suction pipe, so as to impart a rotary motion to liquid in the part of the vessel below said level and means for sucking pulp up the said pipe into the said vessel.

10. Apparatus for a vacuum process of separating materials in a pulp by flotation, comprising a separating vessel, a substantially vertical suction pipe having an increasing cross-section in the upward direction and extending upwardly and co-axially into the said vessel to a level about the middle of the height thereof, radial baffle plates extending from the upper part of the said pipe to the periphery of the said vessel, at least one jet arranged to deliver water under pressure in substantially tangential direction into the part of the said vessel below the said baffle plates so as to impart a rotary motion to liquid in the part of the vessel below said baffle plates and means for sucking pulp up the said pipe into the said vessel.

11. Apparatus for a vacuum process of separating materials in a pulp by flotation, comprising a separating vessel, a conical upper part to this vessel, a delivery throat at the summit of the conical part, a receiver surrounding the said throat and adapted to be

connected with a vacuum pump, a discharge pipe connected with the receiver, an ejector in this discharge pipe, a substantially vertical suction pipe having an increasing cross-section in the upward direction and extending upwardly and co-axially into the said separating vessel, and a discharge pipe connected with the said separating vessel.

12. Apparatus for a vacuum process of separating materials in a pulp by a flotation, comprising a separating vessel, a conical upper part to this vessel, a delivery throat at the summit of the conical part, a receiver surrounding the said throat and adapted to be

connected with a vacuum pump, a discharge pipe connected with the receiver, an ejector in this discharge pipe, a substantially vertical suction pipe having an increasing cross-section in the upward direction and extending upwardly and co-axially into the said separating vessel, a discharge pipe connected with the said separating vessel, a valve closing the lower end of the last-named discharge pipe and means for periodically opening and closing the said valve.

In testimony whereof I have signed my name to this specification.
